190,656

TABLE

Henry P. Glass, Chicago, Ill., assignor to The Lane Company, Inc., Altavista, Va., a corporation of Virginia

Filed Mar. 3, 1960, Ser. No. 59,608

Term of patent 14 years

(Cl. D33—14)

FIG. 1.

FIG. 2.

FIG. 3.

FIGURE 1 is a perspective view of a table showing my new design;

FIGURE 2 is an enlarged fragmentary view of one corner of the table and a portion of one leg; and

FIGURE 3 is a bottom perspective view of the fragmentary portion depicted in FIGURE 2 and showing one of the four identical leg attaching brackets.

I claim:

The ornamental design for a table, substantially as shown and described.

References Cited in the file of this patent

UNITED STATES PATENTS

1,756,777 Wright _____ Apr. 29, 1930
2,184,677 McKay _____ Dec. 26, 1939

OTHER REFERENCES

Hagan Cat. No. 543, 1956, page 789, item C, Table.